DESIGN FOR A MOTOR FOR AN ELECTRICALLY DRIVEN MIXER

Louis Myers, Rockford, Ill.

Application June 4, 1945, Serial No. 119,884

Term of patent 14 years

(Cl. D26—5)

To all whom it may concern:

Be it known that I, Louis Myers, a citizen of the United States, residing at Rockford, in the county of Winnebago and State of Illinois, have invented a new, original, and ornamental Design for a Motor for an Electrically Driven Mixer, of which the following is a specification, reference being had to the accompanying drawing, forming a part thereof.

In the drawing:

Fig. 1 is a front perspective view of a motor for an electrically driven mixer showing my new design.

Fig. 2 is a rear perspective view.

Fig. 3 is a top plan view.

I claim:

The ornamental design for a motor for an electrically driven mixer, substantially as shown.

LOUIS MYERS.
